CLAIM

The ornamental design for a chamfered panel for an office machine, as shown and described.

DESCRIPTION

FIG. 1 is a perspective view of a chamfered panel for an office machine showing the ornamental design in accordance with the present invention;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

The broken lines depict environmental subject matter only and form no part of the claimed design.
